UNITED STATES PATENT OFFICE.

HENRY CLAY BASCOM, OF LANSINGBURG, AND EDWARD AMBROSE, OF TROY, NEW YORK, ASSIGNEES TO H. CLAY BASCOM & CO., OF TROY, NEW YORK.

DESIGN FOR A STOVE.

SPECIFICATION forming part of Design No. 27,724, dated October 12, 1897.

Application filed November 27, 1896. Serial No. 613,699. Term of patent 14 years.

To all whom it may concern:

Be it known that we, HENRY CLAY BASCOM, residing at Lansingburg, and EDWARD AMBROSE, residing at Troy, Rensselaer county, 5 State of New York, citizens of the United States, have invented and produced a new and original Design for Stoves, of which the following is a specification, reference being had to the accompanying drawing, illustrating a 10 stove embodying the elements in our design.

In our design the stove is made up of sections, each of form and with ornamentations as herein described.

A is the base portion of the stove, which portion is rectangular in form and has rounded corners, with which legs *a a* seem to be integral and appear to terminate at the evolute-form scrolls *a' a'*, which form the corner-decorations of this section. These evolute scrolls 20 have palmette terminals *a²* running inwardly toward the middle of each side portion of the side base and receive between them the inverted palmette ornament *a²*.

B is the superbase-plate, also of rectangular form and smaller dimension than base portion A, and has its corners rounded and convex sloping side surfaces bearing a band of palmette ornaments *b b* in oblique arrangement at opposite angles, as shown, while its 30 lower border is with plain surfaces.

C is the ash-pit-wall portion, also of rectangular form and having rounded corners and sides which are convex in vertical direction and bearing in its side portions a central 35 palmette ornament *c* between the foliate ornaments *c' c'* of the rounded corners of said wall portion, as shown.

C' is the ash-pit door, having convex vertical bars and ornamented by foliate ornaments *c²*.

D is a division-plate separating the ash-pit-wall portion from the wall portion surrounding the fire-pot above, which plate is rectangular in outline of form and has rounded corners and flattened convex upper side surfaces bearing palmette-form ornaments *d* and having a plain lower edge border *d'*.

E is the wall portion which surrounds the fire-pot and comprises the rounded vertical

corner-posts *e*, having plain surfaces, and the 50 side rows of bosses *e' e'*, and the doors F.

The doors F are convex in both vertical and horizontal directions and are hinged each to a post *e*. These doors are each of open-work form and comprise the lower, upper, 55 and side bars *f*, horizontal cross-bar *f'*, and vertical cross-bars *f² f²*, and the two reversed similar foliate scrolls *f³ f³*, which each partly cover the openings between the crossing bars *f'* and *f² f²* and the mica openings between. 60

G is a division-band-form part arranged between the wall E, surrounding the fire-pot, and the wall of combustion-chamber H above. This division-band piece bears a scale-form ornamentation *g*, bounded above and below 65 by horizontal border-beadings *g' g'*.

H is wall portion which incloses the combustion-chamber and comprises the corner-pieces *h* and doors *H'*, hinged each to a corner-piece.

The doors *H'* are each convex in both a horizontal and vertical direction and are open-work in form of construction, with its lower end in a straight horizontal line, sides parallel, and upper ends arching and comprising 75 besides the outer framing-bars *i i* the vertical bars *i' i'* and horizontal cross-bars *i² i²*. These doors *H'* are ornamented each by two reversed foliate scrolls *i³ i³*, having portions crossing bars *i' i'* and *i² i²* and running over 80 portions of the mica openings in the lower, upper, and side rows and leaving the central opening substantially wholly uncovered.

I is the close upper end wall portion of the combustion-chamber, which portion bears 85 over each door *H'* the shell-form ornament *j* and projected corners ornamented by rolled scrolls *j'* at each side, with downwardly-extended palmette terminals *j²*.

K is the base of the dome, having a rectangular form and with rounded corners, and is mounted on the upper end of the combustion-chamber section. It is made with an inclining convex surface *k*, having a plain lower border-skirt *k'* and bearing in each corner-quarter a palmette-form ornament *k²*.

L is the central dome, of oblong form and oval, having a convex surface extending from

the horizontal upper plane to the plain lower border-band *m*. Each quarter of this central dome bears a palmette ornament *l*.

What we claim is—

- 5 1. In a design for a stove, the design for the base portion and legs integral therewith, substantially as herein shown and described.
2. In a design for a stove, the design for the superbase portion *B*, substantially as herein shown and described.
- 10 3. In a design for a stove, the design for the ash-pit portion *C* substantially as herein shown and described.
4. In a design for a stove, the design for 15 the ash-pit door *C'*, substantially as herein shown and described.
5. In a design for a stove, the design for the division-plate *D* substantially as shown and described.
- 20 6. In a design for a stove, the design for the wall portion *E* of the fire-pot section, substantially as shown and described.
7. In a design for a stove, the design for the door *F*, in the wall portion *E*, substantially as shown and described.
- 25 8. In a design for a stove, the design for

the ornamental band *G*, adjoining and above the wall portion *E*, substantially as shown and described.

9. In a design for a stove, the design for 30 the wall portion *H*, which incloses the combustion-chamber, substantially as shown and described.

10. In a design for a stove, the design for the door *H'*, of the combustion-chamber of 35 the stove, substantially as shown and described.

11. In a design for a stove, the design for the close upper end wall portion *I*, substantially as shown and described.

12. In a design for a stove, the design for the base *K* of the dome, substantially as shown and described.

13. In a design for a stove, the design for the dome *L* substantially as shown and de- 45 scribed.

H. CLAY BASCOM.
EDWARD AMBROSE.
